PROTECTOR

Howard C. Sternberg, Akron, Ohio

Application March 31, 1937, Serial No. 134,040

2 Claims. (Cl. 2-22)

This invention relates to protectors, and more especially it relates to body protectors such as commonly are worn by athletes for protection to the shoulders, elbows, and knees.

5 The chief objects of the invention are to provide an improved knee pad that may be worn without binding or other discomfort; that will not move out of place while in use; that is naturally shaped to fit the knee of the wearer; and 10 that is inherently resilient longitudinally so as to flex freely and thus to yield to movements of the wearer's limb. Other objects will be manifest as the specification proceeds.

Of the accompanying drawing:

15 Fig. 1 is a side elevation of the protector, in its preferred form, in applied position upon the knee of the user;

Fig. 2 is a rear elevation thereof, on a larger scale, parts being broken away for clearness of 20 illustration;

Fig. 3 is a section, on a larger scale, on the line 3-3 of Fig. 2; and

Fig. 4 is a side elevation of a resilient element of the protector structure.

25 Referring to the drawing, particularly Fig. 1 thereof, there is shown a complete protector comprising a frontpiece or knee pad 10, a retaining strap 11, and a back piece 12. The knee pad 10 is of general scoop shape, that is, its upper 30 portion is concavo-convex both longitudinally and transversely, its lower portion being concavo-convex only in a transverse direction. It is designed to fit snugly over the knee as shown, being held in place by the strap 11 that encircles the leg below the knee and above the calf, the back piece 12 being mounted upon said strap.

The outer or convex surface of the knee pad 10 consists of pliable leather, and is constructed 40 of two pieces or blanks of leather 14, 14 that are stitched together along one margin of each piece to form a seam 15, said margin being arcuate in part so as to impart a natural concavo-convex shape to the assembled leather parts. The leather pieces 14 are slit at 16, 16 to permit the strap 45 to be threaded therethrough, in a direction transversely of the seam 15. Upon the inner or concave side of the seam 15 is positioned a resilient stiffening member or stay 17 that may be of bone or celluloid, but preferably is of spring steel in strip or flat form. As is shown most 50 clearly in Fig. 4, the member 17 is arcuate in

part and thus conforms to the shape of the assembled leather parts 14. The member 17 is held securely in place by a leather strip 18 that overlies said member 17 and is stitched to the leather parts 14.

5 The concave side of the pad is faced with sheepskin 20 with the fleece side exposed so as to be next to the skin of the wearer, the sheepskin preferably being adhered to the leather 14. The peripheral margin of the pad has a binder 10 21 of leather or cloth stitched thereto, which binder covers the exposed edges of the leather 14 and sheepskin 20, and gives the pad a finished appearance.

Like the knee pad 10, the back piece 12 may 15 be constructed of a single piece of leather that is lined with sheepskin, and is suitably slit to receive the strap 11. The back piece prevents the strap from chafing the leg.

Because of the natural scoop shape of the protector, it closely hugs the knee of the wearer 20 and does not slip down even during the most violent exercise. Because of the natural tendency of the pad to stay in position, but one attaching strap is required, and freedom of flexure 25 of the knee is not hampered. The stay 17 normally retains the pad in its preferred shape, but does not hamper flexure of the pad incidental to normal use thereof. The protector is light in weight and achieves the other objects set out 30 in the foregoing statement of objects.

Modification may be resorted to without departing from the spirit of the invention or the scope of the appended claims.

What is claimed is:

35 1. A knee protector comprising a flexible padded structure that is longitudinally arcuate in a portion, at least, of its structure, and a resilient, longitudinally arcuate stay in said structure extending longitudinally thereof and yieldingly 40 maintaining the longitudinally arcuate shape thereof.

2. A knee protector comprising a flexible padded structure that is longitudinally and transversely arcuate in the portion thereof that is disposed above the knee and transversely arcuate in the portion that is disposed below the knee, and a resilient longitudinally extending stay positioned centrally within said structure, said stay being arcuate in the region thereof that is disposed above the knee.

HOWARD C. STERNBERG.
